Application July 1, 1931, Serial No. 548,140

31 Claims. (Cl. 184—7)

This invention relates to spinning and twister frames of the ring type.

In twister frames, and in some spinning frames also, but more especially those twister frames in which a vertical ring is used, it is a common practice to apply grease to the ring by hand in order to reduce the friction of the traveller on the ring. This is necessary more particularly in high speed twisters where the friction of the traveller becomes an important operating factor. Usually it is the practice to grease the ring at every doff. In some cases, however, it is also customary for the machine attendant to apply grease to the rings individually while the frame is running. This is done by stopping the spindles one at a time by means of the knee brake and wiping a small quantity of grease on to the inner surface of the ring by hand.

The lubrication of the rings in this manner is unsatisfactory for many reasons, among which may be mentioned particularly the fact that it is extremely variable, some rings necessarily receiving much more lubricant than others, it requires considerable labor, and the condition of the rings as to lubrication varies from an over supply immediately after the application of the lubricant to an inadequate supply frequently before the next application. This method often results in throwing an excessive amount of lubricant around over adjacent parts of the machinery and the work, which in some cases is extremely objectionable.

The present invention deals especially with these problems. It aims to devise an apparatus for supplying lubricant to the rings of spinning and twister frames more uniformly and in controlled quantities. It is also an object of the invention to reduce the labor required in lubricating rings and to perform this operation automatically.

In view of the fact that the invention is applicable both to spinning and twister frames but is used more generally in the latter type of machine, it will be herein disclosed as applied to a twister frame and both types of machines will be hereinafter included in the term "twister frame."

The nature of the invention will be readily understood from the following description when read in connection with the accompanying drawings, and the novel features will be particularly pointed out in the appended claims.

In the drawings,
55 Figure 1 is an end view of a twister frame

equipped with apparatus embodying features of this invention;

Fig. 2 is a side view of portions of a ring rail and spindle rail of the machine shown in Fig. 1, some of the parts being broken away;

Fig. 3 is a plan view of a section of the ring rail shown in Fig. 2;

Fig. 4 is a vertical, sectional view on a large scale through one ring of the rail shown in Fig. 3, and illustrates also the details of the lubricator 10 and the lubricating fixture associated with the ring;

Fig. 5 is a view similar to Fig. 3 but showing two rings only and illustrating them on a larger scale;

Fig. 6 is a transverse, vertical, sectional view of parts shown in Fig. 5, illustrating more particularly the lubricating apparatus;

Fig. 7 is a fragmentary plan view showing the invention applied to rings of larger size than those shown in Fig. 5;

Fig. 8 is a vertical, sectional view of the construction shown in Fig. 7;

Fig. 9 is a plan view of a mechanism for delivering lubricant to the supply line which feeds the series of rings;

Fig. 10 is a side view, partly in section, of the mechanism shown in Fig. 9;

Fig. 11 is a side view, partly in section, illustrating certain parts of the operating mechanism shown in Figs. 9 and 10; and

Fig. 12 is an end view, partly in section, of the mechanism shown in Fig. 10.

The arrangement shown in the drawings includes a ring rail carrying a series of rings with means for feeding oil from a common source of supply to all of said rings. Referring first to Figs. 2 to 6, inclusive, the ring rail is shown at 2, the rings at 3, and the holders for the rings at 4. Spindles located in operative relationship to certain of the rings are shown in Fig. 2 at 5. All of these parts may be constructed, arranged and operated in the usual manner except for certain details which will be hereinafter described. Usually each ring is pressed into its respective ring holder and each ring holder is secured to the ring rail by screws 6, 7 and 8, as best shown in Fig. 5, the holder being slotted to receive the three screws.

For the purpose of lubricating the rings, oil or other lubricating material is delivered from a common source of supply, as will later be described, to an oil supply line 10 which extends along the rail 2 and preferably is located below the rail in the channel section thereof. This

supply line conducts oil to a series of lubricating fixtures 12 which are associated with the respective rings and ring holders, each fixture preferably being located between two adjacent ring holders and arranged to conduct oil from the supply line to both ring holders with which it is associated. The supply line 10 may conveniently consist of copper tubing and may be connected to the fixtures 12 by fittings of well known forms. 5 Each fixture includes an oil chamber 13, Figs. 4 to 6, through which the oil flows from one section of the supply line to another.

The fixtures 12 are each secured to the lower side of the ring rail by a screw 14, and they are each provided with two short hollow nipples 15—15 which fit somewhat loosely into holes 16 formed in the lower surfaces of the ring holders. Oil is delivered to the fixtures under pressure and flows upwardly through lubricators 17 and 20 through the nipples 15 into the chamber 16, thence through oil ducts 18 in the ring holder and through additional ducts 20 in the rings themselves into grooves 21, one such groove being formed in the upper part of the inner circumferential surface of each ring. A gasket 22, Fig. 4, surrounding each nipple 15 prevents leakage of the oil around the nipple. 25

While the lubricator used may take any one of several forms, the type shown in Fig. 4 has proved 30 very satisfactory. It is of a form readily obtainable on the market and consists of a body which is threaded into an internally threaded bore 23 in the fixture 12, the bottom of this bore being normally closed by a screw threaded plug 24. 35 The lubricator includes a screen 25 holding a body of fibrous material 26 which acts as a filter, the screen being held in place by a ring 27 which is pressed into the body 17. A hole 28 of accurate dimensions is drilled axially in the body 17 and 40 is partly filled by a pin 29. At the upper end of this pin is a valve 30 which normally is held seated by a coiled spring 31 backed up by a cap 32. Each pin 29 is made accurately so that the dimensions through which the oil must escape 45 are practically the same at each lubricator. The springs 31 also are substantially uniform and they hold the heads of the valves seated with a substantial degree of pressure.

It will be clear, therefore, that if a predetermined quantity of oil under sufficient pressure is delivered to the supply line 10, all of the valves 50 30 in the lubricators will be lifted substantially simultaneously, and approximately uniform quantities of oil will be delivered to all of the 55 grooves 21 in the rings. This oil tends to overflow the groove in each ring and to run down the inner surface of the ring and it is distributed around the entire surface of the ring by the traveller. The oil supply may be such that the traveller will act on it to form a meniscus which will 60 persist as the traveller rotates around the ring.

By delivering the oil to the supply line 10 at predetermined intervals and in predetermined quantities, a substantially uniform lubricating 65 condition can be maintained at each ring.

For the purpose of delivering oil to the supply line in this manner, we have provided a pump with mechanism for operating the pump intermittently from the driving mechanism of the 70 twister frame. Referring to Fig. 1 it will be seen that the supply lines 10—10 for the ring rails at the opposite sides of the frame are both connected to a main supply line 35 which leads from a pump cylinder 36, a check valve being located 75 at the outlet of the cylinder to prevent a back

flow of lubricant into the cylinder. This cylinder, as better shown in Fig. 10, is connected to the bottom of a supply tank 37. A piston 38 is mounted to reciprocate in the cylinder 36, the piston including a ball check valve 39. When the piston is lifted the oil flows freely past the ball 39 into the lower part of the cylinder 36, but when the piston later is forced downwardly by the action of the spring 40, the ball check valve closes and the piston forces the oil trapped in the cylinder below it out through the supply lines 35 and 10 to the rings. 10

The mechanism for lifting the piston 38 comprises a cam 41, Figs. 9 to 12, arranged to engage a roll 42 mounted in the end of a forked lever 43 which is fulcrumed on the tank 37 at 44. The piston rod 45 is located between the arms of the lever 43 and is encircled by a cross head 46 which is pivoted to the lever 43 and is backed up by a nut 47 threaded on the piston rod 45. A check 20 nut 48 locks the nut 47 in adjusted position. This arrangement provides a convenient means for adjusting the length of stroke of the piston 38.

The operating mechanism for the pump is conveniently driven from the cam shaft 50, Fig. 1, 25 of the builder motion of the twister frame, this cam shaft, in turn, being driven in the usual manner by a worm gear connection with the driving mechanism for the other parts of the machine including the spindle driving drum and the feed rolls. All of these units are geared together 30 so that the shaft 50 rotates in a definite time relationship to the other driven members of the machine. A sprocket wheel 51 on the cam shaft 50 is connected by a chain 52 with another 35 sprocket wheel 53 on the driving shaft 54 of the pump operating mechanism. This shaft therefore is driven continuously. The mechanism is arranged, however, to rotate the cam 41 once at the end of a predetermined and adjustable interval of time, such rotation serving to raise the piston rod 45 and then release it, thus allowing the spring 40 to depress the piston 38. 40

This mechanism includes a pinion 55 keyed to the driving shaft 54 and adapted to mesh with 45 and drive a gear 56 on the shaft 57 on which the cam 41 is mounted. The teeth of the gear 56, however, have been removed from a certain section so that when this smooth section or gap arrives opposite the pinion 55 the gear 56 and 50 the cam shaft 57 will stop. Movement of these parts is definitely arrested at this time by the engagement of a pin 58, Figs. 11 and 12, with the thickened portion 60 of a catch plate or stop plate 61, the pin 58 being secured rigidly in the 55 gear 56. In order to start these parts into rotation again a pick wheel or ratchet wheel 62 is located loosely on the shaft 57 and is arranged to be rotated step by step by a pawl 63 which is pivoted on an arm 64 mounted to rock on the shaft 60 57, this arm being pivoted to an eccentric strap 65 which is oscillated continuously by an eccentric 66 fast on the driving shaft 54. This shaft turns slowly so that the movement of the pawl 63 is relatively slow. The point in its swing 65 at which it engages the teeth of the pick wheel 62 is controlled by a guard 67 lying closely adjacent to the pick wheel, the pawl 63 running on the surface of this guard. The guard is supported on a stationary plate 68 and is adjustable 70 thereon by means of a bolt and slot connection 70 with said plate 68. The arrangement is such that the pawl 63 may be allowed to move the pick wheel forward from one to a dozen or more teeth, as desired. Consequently, at a time de- 75

terminated by the setting of this guard, a pin 71 which projects rigidly from the pick wheel will strike the lug 72, Fig. 11, projecting from the catch plate and rock this catch plate backwardly 5 about its pivot 73, thus moving the stop lug 60 out of engagement with the pin 58. At this time the pin 74 which projects from the pick wheel 62 will engage another pin 75 projecting from the cam shaft 57 and will move the whole cam 10 shaft forward by an angular distance depending upon the movement imparted to the pick wheel by the pawl 63. This action is also aided by a spring 76, Fig. 12, one end of which is secured to a stationary pin, while its opposite end is 15 secured to a plate 77 that is pivoted to an eccentric stud 78 projecting from the end of the cam shaft, the arrangement being such that this spring tends to rotate the cam shaft in the same direction in which it is rotated by the action of the pin 74 on the pin 75. These parts give the gap gear 56 a sufficient rotative movement to bring its teeth into mesh with those of the driving pinion 55, whereupon the cam shaft 57 is given one complete revolution and is then 20 stopped again, the operations above described being repeated so long as the machine continues to run.

In order to avoid any possibility of breaking the parts in the event that the gears are not brought into proper mesh at the end of the picking operation, the gear 56 is mounted on a squared portion 80, Fig. 11, of the cam shaft 57, and is provided with a rectangular hole into which the squared part 80 fits. A spring 81 acts 25 between the gear and the part 80 to hold the gear normally centered on the shaft, but permits the movement of the gap gear 56 away from the driving pinion in the event that the teeth do not mesh properly. This permits some slip 30 to occur between the gears when the gap gear starts up which will result in bringing them into proper mesh. A dog 79 pivoted on the stationary plate 68 engages the pick wheel 62 and prevents reverse rotation of this wheel. While 35 the cam shaft 57 is making its revolution, the pin 75 catches up with the pin 74 and moves the pick wheel 62 far enough to carry the pin 71 past the lug 72 on the catch plate 61 before the rotation of the cam shaft is stopped. This leaves 40 the parts in approximately the position shown in Fig. 11 in readiness for the picking operation to begin again.

The oil tank 37 is equipped with a filling spout 33, the end of which normally is closed by a pivoted cover 34.

When the twister frame is in operation the apparatus above described operates automatically to deliver oil in approximately predetermined quantities and at predetermined intervals to all 45 of the rings in the ring rail of the machine. The length of these intervals can be adjusted by 50 adjusting the guard 67, as above described, to predetermine the amount which the pick wheel will be advanced by each stroke of the pawl. The 55 quantity of oil delivered at each interval can be predetermined by adjusting the nuts 47 and 48 on the pump piston rod 45, so as to adjust the operating stroke of the pump. The arrangement is such that the pressure of the oil at all of 60 the lubricators is substantially the same. The lubricators control the flow of the oil from the oil supply line to the respective rings with which 65 they are associated so that approximately the same quantity of oil is delivered to each ring. 70 This arrangement, therefore, relieves the oper-

ator from any duty connected with the lubrication of the rings. At the same time it provides a far more constant and uniform supply of lubricant to the rings than has been obtainable heretofore, avoiding both the excessive over supply at times and the inadequate supply at other times which has been an important objection to prior methods. 75

In some machines it is desirable to provide for the manual control of the pump operating mechanism so that the pump can be brought into 10 operation by hand at any desired time, as for example, when the machine attendant is starting up the twister after the doffing operation has been completed. For this purpose a rod 86, Fig. 1, is pivoted to the catch plate 61 and runs to an 15 arm 87 secured on a rock shaft 88 which is mounted in the end frame 90 of the machine. At the opposite side of the frame plate a handle 91 is secured to the rock shaft 88 so that by depressing this handle the catch plate 61 can be 20 rocked far enough to release the pin 58, Fig. 11, in the same way that it is released automatically by the mechanism above described.

A somewhat different arrangement is shown 25 in Figs. 7 and 8 adapted for use with large rings. Each of these rings 3' is provided with a groove 92, Fig. 8, extending around the entire circumference of the ring and which communicates through ducts 93 with a groove 21' like that formed in the rings 3. This ring has an intermediate bearing portion 94 which is engaged by the knee of the traveller T. Oil flows down over this surface and part of the oil flows through holes 95 to the outside of the ring where it serves to lubricate the surface on which the heel of the traveller rides. A duct 96 is provided in the ring holder to carry oil to the groove 92. In this arrangement the lubricators 17' are simply forced 30 into holes in the fixture 12' and the oil escapes 35 at the upper end of each lubricator through a hole drilled laterally through the wall of the fixture 12'. 40

In this construction some clearance is allowed 45 between each nipple 15' and the hole therefor in the ring holder so that the holder can be adjusted independently of the fixture and without disturbing the operative relationship of the fixture to the holder. A similar clearance is provided for this purpose in the construction shown 50 in Fig. 4.

While we have herein shown and described a preferred embodiment of our invention, it will be understood that the invention may be embodied in other forms without departing from 55 the spirit or scope thereof. It should also be understood that while we have referred particularly to the lubricating material as oil, since this is the material which we prefer to use, other lubricants could be used with minor modifications of the system shown. The term "oil", therefore, as hereinafter used in the claims should be understood to include other lubricants. 60

Having thus described our invention, what we desire to claim as new is:

1. In a twister frame, the combination with a ring rail and a series of rings mounted on said rail, of means for delivering oil to all of said rings and distributing said oil substantially uniformly to the individual rings, said means including a conduit running along one side of the rail adjacent the lower edge thereof and a plurality of junction flow regulating devices, each having a pair of parallel vertical sockets, enclosing flow metering devices, connected to said 75

- conduit and extending upwardly to feed said rings.
2. In a twister frame, the combination with a ring rail and a series of rings mounted on said rail, of a ring holder for each ring, a fixture operatively associated with each ring, means for conducting oil from a common source of supply to all of said fixtures, means in each fixture for controlling the flow of oil therethrough to its respective ring, and means for supporting said holder for adjustment independently of said fixture and while maintaining the operative relationship of said fixture to said holder substantially undisturbed.
3. In a twister frame, the combination of a ring rail and a series of rings mounted thereon, a ring holder for each ring, communicating oil ducts in said rings and holders, an oil supply, an oil supply line to carry oil from said supply to the ducts in the holders, and lubricators mounted in said supply line adjacent said holders to control the flow of oil from said line to said holders and thence to the ducts in said rings, said lubricator including a junction fitting having an inlet arranged for the attachment of a conduit, an outlet similarly arranged, a plurality of sockets, drip plugs in the inner ends of said sockets, attachment means in the outer ends of said sockets plugging the same and connecting the fitting to the holder, and another attachment means connecting the fitting to the frame.
4. A lubricating installation for a twister frame involving an elongated rail structural member having a multiplicity of closely associated apertures therethrough, annular plate holders positioned upon the edges of said apertures, fixed ring bearing elements, and movable rider bearing elements, each bearing requiring an occasional small supply of lubricant; said installation comprising a main feed conduit longitudinal of and substantially rigid with said structural member and in protected position in respect thereto, a socket carrying element adjacent each ring, branch conduits from said main conduit to one side of said sockets and from the other side of said sockets to and then through the respective holders and rings, flow delivery elements including flow proportioning restriction means in each of said sockets preventing communication from the inlet to the outlet sides of the sockets except through the restriction means, a lubricant inlet for said main conduit, and means for maintaining said main and branch conduits substantially filled with lubricant during the intervals between lubricating operations.
5. A lubricating installation for a machine of the type involving an elongated structural member having a multiplicity of closely associated apertures therethrough, fixed bearing elements in said apertures each supporting a movable bearing element, each bearing requiring an occasional small supply of lubricant; said installation comprising a main feed conduit longitudinal of and substantially rigid with said structural member and in protected position in respect thereto, socket carrying elements adjacent each device with vertical sockets transverse to said conduit, branch conduits from said main conduit to one side of said sockets and upwardly inclined from the other side of said sockets to and then through said fixed bearing elements, highly restricted drip plug metering elements including flow proportioning restriction means in each of said sockets prevent communication from the inlet to the outlet sides of the sockets except through the re-
- striction means, a lubricant inlet at one end of said main conduit, and means for maintaining said main and branch conduits substantially filled with lubricant during the intervals between lubricating operations.
6. A lubricating installation for a machine of the type involving an elongated structural member having a multiplicity of closely associated apertures therethrough, fixed bearing elements in said apertures, each supporting a movable bearing element, each bearing requiring an occasional small supply of lubricant; said installation comprising a main feed conduit longitudinal of and substantially rigid with structural member and in protected position in respect thereto, junction elements adjacent each device with a pair of vertical sockets, branch conduits from said main conduit to the bottom of said sockets and upwardly inclined from the upper end of said sockets to and then through said fixed bearing elements, highly restricted drip plug metering elements including flow proportioning restriction means in each of said sockets preventing communication from the inlet to the outlet sides of the sockets except through the restriction means, a lubricant inlet at one end of said main conduit, distributing troughs associated with said fixed bearing elements, and means for maintaining said main and branch conduits up to said troughs substantially filled with lubricant during the intervals between lubricating operations.
7. A lubricating installation for the rings of a channel ring rail for spinning and twisting machines having a plurality of rings comprising a conduit system extending the length of the ring rail inside the channel along one side thereof and supported thereby, a lubricant pressure and supply means connected to said conduit, a series of vertically positioned elongated flow metering devices suspended from the ring rail and extending upwardly toward said bearings and connecting conduits establishing communication between said conduit system and the lower ends of said flow metering devices, and the upper ends thereof and said rings.
8. A lubricating installation for a channel ring rail for spinning and twisting machines comprising a horizontal conduit extending the length of the ring rail and inside the channel thereof, a lubricant pressure and supply means connected to one end of said conduit, a series of vertical drip plugs inside of said channel positioned closely adjacent to said rings, one for each ring, also positioned within the channel of the ring rail and connecting conduits establishing communication between said conduit, said drip plugs and said rings.
9. In combination with a lubricated channel ring rail construction including a rail with a series of rings rigidly fixed therewithin, a lubricating installation positioned within said channel, said rings having circumferential shoulders upon the interior surfaces thereof, and bores extending upwardly and radially through the rings admitting lubricant from the exterior thereof to the said shoulders, said installation feeding said bores, and an inlet for said installation at the exterior of the rail.
10. A lubricated channel ring rail construction including a ring rail with a series of openings with rings fixed therewithin, said construction comprising collecting troughs extending entirely around each of said rings substantially below the tops thereof, external conduits along the

rails inside of the channel and interior bores through the rings for supplying lubricant to said troughs and an inlet to the said conduits.

11. In combination with a machine including

5 a channel like structure with a series of bearings having fixed bearing elements and movable bearing elements, a lubricating installation comprising a lubricant inlet, lubricant bores extending through the body of the machine to and through 10 said fixed bearing elements from said inlet, fittings containing sockets upon said conduits adjacent said fixed bearing elements clamped to said fixed elements inside of said channel, said sockets being accessible from the outside of the 15 machine, plugs completely enclosed in said sockets for determining the flow of lubricant through the conduits and additional plugs sealing the outside of said sockets.

12. In combination with a machine including

20 series of spaced bearings with fixed and movable bearing elements; a lubricating installation comprising a lubricant inlet, a branched distribution system extending from said inlet to and through said fixed bearing elements, said 25 system consisting in substantial part of bores through the machine structure, a series of fittings carrying tapped sockets clamped to said machine structure, one socket being positioned in each branch and each socket being so positioned 30 as to be readily accessible from the exterior of the machine, a series of threaded drip plugs completely enclosed in said sockets and means for closing the open ends of said sockets.

13. In a lubricated mechanism including an

35 elongated channel-like structural member, holders bolted thereto carrying a series of ring bearings, a lubricating installation comprising a lubricant inlet, an external conduit extending along the length of said structural member and adjacent one of the sides thereof inside of said 40 channel, a series of socket carrying fittings positioned along the side of the structure inside of said channel, substantially one socket being provided for each bearing element and each socket 45 communicating with said conduit and branched conduits including nipple members on said fittings and receiving sockets in said holders transverse to said external conduit leading from each 50 of said sockets to said bearings, flow metering devices plugging and completely enclosed in each of said sockets and preventing passage of lubricant through said sockets except through said devices and bolts connected to said structure clamping said nipple members into said receiving 55 sockets.

14. In a lubrication installation for a channel-like structure, holders bolted thereto having bearings with fixed and moving elements and an attached structure bolted to said structure and

60 connected to said holders, said holders having inlet sockets on their lower surfaces and lubricant passageways and said attached structure being positioned inside of said channel and having a lubricant conduit system therein with enlarged 65 socket portions and with outlet nipples, flow controlling elements completely enclosed in said socket portions restricting the lubricant flow through said conduit system, a coupling arrangement for an inlet connection attaching the same to the inlet of the conduit system and gasket means encircling the connection of the outlet nipples and inlet sockets assuring a liquid-tight lubricant transfer.

70 15. In a lubrication installation for a channel-like structure, holders bolted thereto having

bearings with fixed and moving elements and an attached structure bolted to said structure and connected to said holders, said holders having inlet sockets on their lower surfaces and lubricant passageways and said attached structure being positioned inside of said channel and having a lubricant conduit system therein with enlarged 10 socket portions and with outlet nipples, flow controlling elements completely enclosed in said socket portions restricting the lubricant flow through said conduit system, a coupling arrangement for an inlet connection attaching the same to inlet of the conduit system and gasket means encircling the connection of the outlet nipples and inlet sockets assuring a liquid-tight lubricant transfer, the socket portions being arranged in parallelism to each other and the inlet portions of the conduit system being transverse to said socket portions.

16. In a lubrication installation for a channel-

like structure, holders bolted thereto having bearings with fixed and moving elements and an attached structure bolted to said structure and connected to said holders, said holders having inlet sockets on their lower surfaces and lubricant passageways and said attached structure being positioned inside of said channel and having a lubricant conduit system therein with enlarged socket portions and with outlet nipples, flow controlling elements completely enclosed in said socket portions restricting the lubricant flow through said conduit system, a coupling arrangement for an inlet connection attaching the same to inlet of the conduit system and gasket means encircling the connection of the outlet nipples and inlet 35 sockets assuring a liquid-tight lubricant transfer, the flow controlling elements including flow proportioning restriction means having deformable portions deformed by cooperation with the sockets so as to prevent lubricant passing through 40 the elements except through the restriction means.

17. In a lubrication installation for a channel-like structure, holders bolted thereto having bearings with fixed and moving elements and an attached structure bolted to said structure and connected to said holders, said holders having inlet

45 sockets on their lower surfaces and lubricant passageways and said attached structure being positioned inside of said channel and having a lubricant conduit system therein with enlarged socket portions and with outlet nipples, flow controlling elements completely enclosed in said socket portions restricting the lubricant flow through said conduit system, a coupling arrangement for an 50 inlet connection attaching the same to inlet of the conduit system and gasket means encircling the connection of the outlet nipples and inlet sockets assuring a liquid-tight lubricant transfer, said flow controlling elements consisting of lubricant-tight annular plugs which are in turn filled with restriction plugs permitting slow passage of 55 lubricant.

18. In a lubrication installation for a channel-

like structure, holders bolted thereto having bearings with fixed and moving elements and an attached structure bolted to said structure and connected to said holders, said holders having inlet sockets on their lower surfaces and lubricant passageways and said attached structure being 65 positioned inside of said channel and having a lubricant conduit system therein with enlarged socket portions and with outlet nipples, flow controlling elements completely enclosed in said 70 socket portions restricting the lubricant flow.

- through said conduit system, a coupling arrangement for an inlet connection attaching the same to inlet of the conduit system and gasket means encircling the connection of the outlet nipples 5 and inlet sockets assuring a liquid-tight lubricant transfer, the attached structure being provided with additional tapped sockets for receiving bolts for attachment to the channel structure.
19. In a lubrication installation for a channel-like structure, holders bolted thereto having bearings with fixed and moving elements and an attached structure bolted to said structure and connected to said holders, said holders having inlet sockets on their lower surfaces and lubricant passageways and said attached structure being positioned inside of said channel and having a lubricant conduit system therein with enlarged socket portions and with outlet nipples, flow controlling elements completely enclosed in said socket portions restricting the lubricant flow through said conduit system, a coupling arrangement for an inlet connection attaching the same to inlet of the conduit system and gasket means encircling the connection of the outlet nipples and inlet 15 sockets assuring a liquid-tight lubricant transfer, the socket portions being tapped, receiving threaded plugging means and being provided with cooperating gaskets to prevent leakage.
20. In a twister frame, the combination with a ring rail, said rail being provided with depending flange means, and a series of rings mounted on said rail, of means for feeding oil simultaneously to all of said rings, said means including a conduit running along one side of the rail inside 25 of said flange means and a plurality of junction fittings also positioned inside of said flange means, each having a plurality of sockets including flow regulating devices, each being connected to said conduit and each having outlet 30 means extending upwardly to feed said rings.
21. In a twister frame, the combination with a ring rail, said rail being provided with depending flange means, and a series of rings mounted on said rail, of means for feeding oil from a common source of supply to all of said rings, said means including a conduit running along one side of the rail inside of said flange means and a plurality of junction fittings also positioned inside of 35 said flange means, each having a plurality of sockets including flow regulating devices, one fitting being provided for each pair of rings, each being connected to said conduit and each having outlet means extending upwardly to feed said rings.
22. In a twister frame, the combination with a ring rail and a series of rings mounted on said rail, of a ring holder for each ring, a unitary junction fitting with a plurality of sockets operatively associated with each ring, means for conducting oil from a source of supply to all of said 40 fittings, and means in the sockets of said fittings for controlling the flow of oil therethrough to its respective ring, said fittings each having a single inlet to receive lubricant, a plurality of outlets to said rings and another outlet to the next fitting.
23. In a twister frame, the combination with a ring rail and a series of rings mounted on said rail, of a ring holder for each ring, a unitary junction fitting with a plurality of sockets operatively associated with each ring, means for conducting oil from a source of supply to said fittings, 45 and a lubricator flow metering device removably mounted in each socket of each fitting for controlling the flow of oil therethrough to its respective ring, said fittings each having a single inlet to
- receive lubricant, a plurality of outlets to said rings and another outlet to the next fitting.
24. In a twister frame, the combination with a ring rail and a series of rings mounted on said rail, of a fixture consisting of unitary cast fittings with a plurality of sockets secured to said rail between each pair of adjacent rings, a supply line for conducting oil to all of said fixtures, and drip plug inserts in each of the sockets of each fixture for controlling the flow of lubricant to both rings with which it is associated.
25. In a twister frame, the combination with a ring rail, a ring holder mounted therein, a ring mounted in said holder and adapted to support a traveller, said ring and holder having transverse oil ducts communicating with each other, a peripheral shoulder inside of each of said rings for receiving lubricant from said ducts adjacent the upper edges of said rings, and means for supplying oil to said ducts.
26. In a twister frame, the combination with a ring rail, a ring holder mounted therein, a ring mounted in said holder and adapted to support a traveller, said ring and holder having transverse oil ducts communicating with each other, a lubricating fixture connected to said holder for conducting oil to the duct in said holder, a peripheral ledge inside of each of said rings for receiving lubricant from said ducts adjacent the upper edges of said rings, and an oil supply line for conducting oil to said fixture.
27. In a twister frame, the combination of a ring rail, a ring holder mounted thereon, a ring supported in said holder, said ring being provided with a transverse oil duct, and said holder having a transverse duct communicating with the oil duct in said ring, a peripheral ledge inside of each of said rings for receiving lubricant from said ducts, adjacent the upper edges of said rings, a fixture secured to the lower side of said ring rail, and means for conducting oil to said fixture, said fixture having an oil duct communicating with the duct in said holder.
28. In a twister frame, a ring holder mounted therein, a ring having an oil duct, a lubricator mounted adjacent said ring, an oil passage between said lubricator and the duct in said ring, an oil supply line for conducting oil to said lubricator, and means for pumping oil through said supply line, said lubricator including a junction fitting having an inlet arranged for the attachment of a conduit, an outlet similarly arranged, a plurality of sockets, drip plugs in the inner ends of said sockets, attachment means in the outer ends of said sockets plugging the same and connecting the fitting to the holder, another attachment means connecting the fitting to the frame, and bolt and gasket means causing a lubricant tight connection between said holder and said sockets.
29. In a twister frame, the combination with a ring rail, a ring holder mounted therein, a ring mounted in said holder and adapted to support a traveller, said ring and holder having communicating oil ducts, a lubricator mounted adjacent said holder and communicating with the duct therein, and an oil supply line for conducting oil to said lubricator, said lubricator including a junction fitting having an inlet arranged for the attachment of a conduit, an outlet similarly arranged, a plurality of sockets, drip plugs in the inner ends of said sockets, threaded plugs in the outer ends of said sockets, attachment means connecting the fitting to the frame, and bolt and gasket means causing a lubricant tight connection between said holder and said sockets.

gasket means causing a lubricant tight connection between said holder and said sockets.

30. As an article of manufacture, a channel ring rail for spinning and twisting machines having incorporated therewith an external conduit extending the length thereof inside of said channel, coupling means enabling the connection of a pipe to said conduit, a series of socketted junction means including flow metering devices, one means for each pair of rings and one device for each ring, and internal connecting bores establishing communication between said main conduit, said flow metering devices and said rings.

31. In combination with a machine including series of spaced bearings with fixed and movable bearing elements; a lubricating installation comprising a lubricant inlet, a branched distribution system extending from said inlet to and through said fixed bearing elements, said system consisting

in substantial part of bores through the machine structure, a series of fittings carrying tapped sockets clamped to said machine structure, one socket being positioned in each branch and each socket being so positioned as to be readily accessible from the exterior of the machine, a series of threaded drip plugs completely enclosed in said sockets and means for closing the open ends of said sockets, the bottoms of the sockets being provided with conical depressions and the cooperating ends of the drip plugs being provided with noses of such shape as to effect lubricant-tight connections with said depressions and to seal the inlet portion of the socket from the outlet portion thereof except through the drip plug.
